UNITED STATES PATENT OFFICE.

HIRAM G. WILSON, OF MINNEAPOLIS, MINNESOTA, ASSIGNOR TO JOHN C. HIGDON, OF WASHINGTON, DISTRICT OF COLUMBIA.

DESIGN FOR A GAS-STOVE.

SPECIFICATION forming part of Design No. 19,281, dated August 20, 1889.

Application filed July 23, 1889. Serial No. 318,431. Term of patent 14 years.

To all whom it may concern:

Be it known that I, HIRAM G. WILSON, of Minneapolis, Hennepin county, State of Minnesota, have invented and produced a new and original Design for Gas-Stoves, of which the following is a full, clear, and exact description, reference being had to the accompanying drawings, forming a part hereof.

My invention consists in a design for a gas-stove, and is fully described hereinafter in connection with the accompanying drawings, wherein—

Figure 1 is a view of a gas-stove embodying my design, shown in sectional perspective; 15 and Fig. 2 is a perspective view of the cones forming a part of the design.

The essential or leading feature of the design consists in a casing A, having upper and lower inclosing heads or ends B B', and within 20 which are arranged inverted hollow cones D E F, the walls of which are in parallel planes, the apexes of said cones D and F being in perfect form, while the cone E is of truncated form. This series of cones consists of three 25 members, as shown in the drawings, and said cones are provided with central and peripheral openings, alternately, as shown, but are otherwise perfect in form and outline. The lower cone D is provided with a peripheral opening 30 a, the upper cone F is provided with a similar peripheral opening a, and the intermediate cone is provided with a central opening a' and

a peripheral vertical projection b, as shown. The upper and lower ends B B' of the casing are provided with central openings in vertical 35 alignment with each other, above which are arranged hollow projections G and C, respectively. The bases of the cones, as will be seen, are arranged in planes parallel with the upper and lower ends of the casing, whereby the convergent walls of the cones are arranged in 40 planes which are parallel to each other, and the several apexes of the cones are in alignment with the projections G and C and also with each other. The casing thus has its 45 interior surface unbroken and devoid of all other openings and projections than centrally located and aligned ones.

Having thus described my design, I claim—

The design for a gas-stove herein described, 50 consisting of a casing having upper and lower closed ends provided with centrally-located openings and hollow projections, and the inverted hollow cones D E F, arranged within said casing with their walls in parallel planes 55 and provided alternately with central and peripheral openings, substantially as shown and described.

In testimony whereof I affix my signature in presence of two witnesses.

HIRAM G. WILSON.
